United States Patent Office

Des. 193,070
Patented June 19, 1962

193,070

BOTTLE CASE OR SIMILAR ARTICLE

John Aloysius Friday, Jr., Pittsburgh, Pa., assignor to Duquesne Brewing Company of Pittsburgh, Pittsburgh,
Pa., a corporation of Pennsylvania

Filed July 10, 1961, Ser. No. 65,869

Term of patent 14 years

(Cl. D58—12.6)

FIG. 1

FIG. 2

FIGURE 1 is a three-quarter perspective frontal view of a bottle case illustrating my new design;

I claim:

The ornamental design for a bottle case or similar article, as shown and described.
